UNITED STATES PATENT OFFICE

170,969

CEMENT TRANSPORT TRAILER

Carroll C. Clough, Seattle, Wash.

Application August 17, 1953, Serial No. 26,476

Term of patent 14 years

(Cl. D14—3)

To all whom it may concern:

Be it known that I, Carroll C. Clough, of Seattle, King County, Washington, have invented a new, original, and ornamental Design for a Cement Transport Trailer, of which the following is a specification, reference being had to the accompanying drawings, forming a part hereof.

Figure 1 is a perspective view in the nature of a side elevational view of a cement transport trailer, illustrating my new design.

Figure 2 is a plan view illustrating the design.

Figure 3 is a rear end elevation, also illustrating the design, and Figure 4 is a perspective view from slightly above and looking rearward from the

right forward side, also illustrating the design.

The dominant feature of my design resides in the full line portion of the drawing.

I claim:

The ornamental design for a cement transport trailer, substantially as shown and described.

CARROLL C. CLOUGH.
